(57) **CLAIM**

The ornamental design for a multiple cartridge case gauge, as shown.

DESCRIPTION

FIG. 1 is a perspective view of a multiple cartridge case gauge;

FIG. 2 is a front elevational view thereof;

FIG. 3 is a slightly enlarged rear elevational view thereof;

FIG. 4 is a side elevational view, the opposite side being a mirror image thereof;

FIG. 5 is a top rear perspective view thereof; and,

FIG. 6 is a reduced bottom perspective view thereof.

Stippling in the figures shows contour and not surface ornamentation.
